UNITED STATES PATENT OFFICE.

JOSEPH A. MAYNARD, OF BOSTON, MASSACHUSETTS.

DESIGN FOR A BATH-TRAP.

46,789.

Specification for Design.

Patented Dec. 22, 1914.

Application filed July 27, 1914. Serial No. 853,482. Term of patent 14 years.

To all whom it may concern:

Be it known that I, JOSEPH A. MAYNARD, a citizen of the United States, residing at Boston, in the county of Suffolk and State of Massachusetts, have invented a new, original, and ornamental Design for a Bath-Trap, of which the following is a specification, reference being had to the accompanying drawings, forming a part thereof.

In the drawings Figure 1 is a view in perspective of a bath trap showing my new design. Fig. 2 is a side elevation of the device shown in Fig. 1.

The dotted lines in Fig. 2 form no part of the design but indicate the location of the pipes to which the bath trap is connected.

I claim:

The ornamental design for a bath trap as shown.

JOSEPH A. MAYNARD.
